United States Patent Office

Des. 216,910
Patented Mar. 17, 1970

216,910

LAMP OR SIMILAR ARTICLE

Frank Skupien, 5443 S. Walcott,
Chicago, Ill. 60609

Filed Apr. 15, 1969, Ser. No. 16,756

Term of patent 14 years

Int. Cl. D26—02

U.S. Cl. D48—20

Fig. 3

Fig. 1

Fig. 2

Fig. 4

FIGURE 1 is a perspective view of a lamp or similar article embodying my new design.

FIGURE 2 is a side elevational view thereof.

FIGURE 3 is an end elevational view, the shade and socket elements being omitted for convenience of illustration.

FIGURE 4 is a view taken partly in section on line 4—4 in FIGURE 2, the tubular socket support member being fragmentarily shown for convenience of illustration.

The surfaces not shown are substantially the same as those of the corresponding surfaces shown.

I claim:

The ornamental design for a lamp or similar article, as shown and described.
